SLIPPER INSERT

Filed Aug. 23, 1928

Inventor

Albert Carlson,

By *Chas. A. O'Brien*
Attorney

UNITED STATES PATENT OFFICE.

ALBERT CARLSON, OF PRINCETON, ILLINOIS.

SLIPPER INSERT.

Application filed August 23, 1928. Serial No. 301,497.

This invention relates to an improved device for use in association with footwear, the same being in the form of a special heel lining for slippers, shoes, pumps and the like.

5 The purpose of the invention is to provide a dependable means which functions to prevent up or down slipping of the heel portion of the shoe while the wearer is walking.

In carrying out the invention, I provide a 10 simple and inexpensive device made up of a combination of leather and rubber or equivalent material, the same being shaped and designed to fit comfortably into the heel portion of the shoe and to fulfill the requirements in 15 a dependable and efficient manner.

In the drawings:—

Figure 1 is a fragmentary view in section and elevation, showing the manner in which the device is positioned in a heel of a slipper.

20 Fig. 2 is a top plan view of the same.

Fig. 3 is a plan view of the device removed from the slipper.

Fig. 4 is a cross sectional view taken proximity upon the plane of the line 4—4 25 of Fig. 3.

The device is generally designated by the reference character 5 and as before stated is shaped to fit in the heel portion of the shoe in the manner shown, but it may be made of kid, 30 calfskin, sheepskin, or any desirable flexible leather.

It may be composed of duplicate halves 6, attached or otherwise joined together as at 7, to form a sort of a hinge, adjacent which are 35 vertically spaced stays 8. On opposite sides of the stays are pockets 9, each of which are constructed to accommodate a sponge rubber filler or inset 10. The inset is of general circular design and has a pendent portion 11, at 40 its bottom. Its effective surface is disposed inwardly so that it may rest in contact with the heel portion of the stocking.

It is to be noted from Fig. 4, that the inset 45 functions as an elastic cushion and is tapered downwardly to insure comfort and efficiency. The end portions of the halves 6 terminate in extensions or wings 12, which better conform to the interior of the slipper as shown in Fig.

1. Also the lower edge portion is in the form 50 of a flap 13 which is turned in and disposed beneath the insole.

The invention when in place, as shown in the drawings, acts as a filler, and the sponge-like cushions literally cling to the stockings of the wearer, and because of the shape and location, the appliance prevents loose movement or up and down slipping of otherwise improperly fitted shoes.

Attention is invited to the fact that the invention may be in the form of a separate insert for footwear or it may be a permanent part of the footwear, built in at the time of manufacture.

It is thought that by considering the description of the drawings in connection with the drawings, a clear understanding of the construction and advantages of the invention will be had. Therefore, a more lengthy description is regarded unnecessary.

Minor changes in shape, size, and rearrangement of features may be resorted to within the field of the adjoined claims.

Having thus described my invention, what I claim as new is:—

1. As a new product of manufacture, a shoe 75 lining device of the class described comprising an elongated flexible body including a pair of half-sections hingedly connected together, the lower edge portion of the body being formed to provide a flap for disposition beneath the insole, portions of the body on opposite sides of the hinge being formed into pockets, and a pair of substantially circular sponge rubber insets disposed in said pockets to function as cushions and anti-slipping 80 means.

2. In a shoe construction of the class described, a lining comprising an elongated flexible body including a pair of half sections hingedly connected together, the lower edge 90 portion of the body being formed to provide a flap for disposition beneath the insole, portions of the body on opposite sides of the hinge being formed into pockets, and a pair of substantially circular sponge rubber insets 95 disposed in said pockets to function as cushions and anti-slipping means.

In testimony whereof I affix my signature.

ALBERT CARLSON.
